United States Patent Office.

WILLIAM R. LOUNT, OF AUSTIN, TEXAS.

Letters Patent No. 96,245, dated October 26, 1869.

IMPROVED COMPOUND FOR TREATING THE HUMAN HAIR

The Schedule referred to in these Letters Patent and making part of the same.

I, WILLIAM R. LOUNT, of Austin, Travis county, and State of Texas, have invented a new and useful Compound for Straightening, Softening, and Renewing the Human Hair; and I hereby declare the following to be a full and exact description of the same.

The nature of my invention consists in combining the following materials in about the proportions specified, the essential ingredient being the oil of wild cucumber, one-half pint, with one gallon linseed-oil, four pounds beeswax, four pounds spermaceti, and four pounds white rosin.

Those materials are to be combined by melting them together.

I do not confine myself to the proportions named.

Other fats, oils, or resins may be used instead of the linseed-oil, wax, rosin, and spermaceti.

Having thus described my invention,

What I claim, and desire to secure by Letters Patent of the United States, is—

The compound, substantially as herein described, prepared by combining the oil of the wild cucumber, (*or Acuminata*.) with either or all of the other materials herein named, or their equivalent.

WM. R. LOUNT.
